UNITED STATES PATENT OFFICE

JOHN J. FLOYD, OF EVERETT, MASSACHUSETTS

CAN OPENER OF THE TYPE MORE PROPERLY TERMED COVER LIFTER

Application filed June 14, 1929. Serial No. 371,038.

This invention relates to can openers of the type more properly termed cover lifters. It has for its purposes to provide a simple, inexpensive device by means of which a cover 5 may readily be removed from a can without deforming or otherwise injuring either the can or the cover.

My device is particularly adaptable for use by printers in opening the commercial type 10 of can in which printing inks are delivered and used. It is, however, equally advantageous for use in opening coffee or tea containers, etc. of the well known type in which the cover is in the form of a cap which fits 15 slidably over the end of the can and which as a rule is sealed by a paper label overlapping the can and the cover.

To accomplish the objects of my invention by 20 mounting on a suitable pistol grip or handle which acts as a lever, 1—a paper cutting blade for use in event a sealing of the cover has been effected by a label, 2—a fixed pointed bar which acts as a fulcrum, and 3—a movable spring resistance block or lifter adaptable 25 to fit under the edge of the cover. When it is desired to open a can, the label if any is cut by the paper cutting blade, the resistance block is inserted under the edge of the cover, pressure in the direction of the cover is 30 exerted on the handle until the fixed pointed bar contacts with the can just below the edge of the cover. The handle is then turned on the pointed bar as a pivot so as to cause the resistance block to move in a direction away 35 from the bottom of the can and thus, being positioned under the edge of the cover, forces the cover from the can. Lack of injury to the cover is assured by a turning of the resistance block in its mounting, so that at all times 40 during use a flat side thereof and a flat side only contacts with the cover's edge. In this manner, pressure on the edge of the cover is spread over a flat surface of the resistance block and no injury to the cover results, means 45 being provided whereby the resistance block is caused to return to a normal position after removal of a cover from a can has been effected.

Referring to the accompanying drawings 50 which form a part of this specification, Fig-

ure 1 is a side view of my complete device. Figure 2 is a sectional view of the left mounting shown in Figure 1, and referred to herein as the movable spring resistance block or lifter. Figure 3 is a view of the movable 55 spring resistance block at right angles to the view shown in Figure 2. Figure 4 is a perspective view showing the initial application of the device to a can from which it is desired to remove the cover, the resistance block being 60 inserted under the edge of the cover. Figure 5 is a view similar to Fig. 4 showing the position of the device when pressure in the direction of the can is exerted on the handle. Figure 6 is a view similar to Figs. 4 and 5 65 showing the position of the device after the handle is turned to effect removal of the cover from the can.

Referring to the drawings in detail, it will 70 be observed that the present device is inclusive essentially of a handle, the body portion of which is designated as A and the finger grip portion of which is designated as B.

Mounted to project at a suitable point 75 from the body portion A of the handle, preferably from the inner end thereof, is a blade C for use as a label cutter in instances where a sealing label is disposed around the can J and overlaps the cover K of the can. Also mounted to project from the inner end of the body portion A of the handle is a pivot pin D, the outer or free end of which preferably is sharpened as shown for engagement 80 between the inner edge of the cover K and the usual annular rib on the can against which the inner edge of the cover usually abuts.

Adjacent to the pivot pin D, the body portion A of the handle is provided with a longitudinally extending bore in which is fixed 85 a sleeve H. Mounted in this sleeve for rotation and for longitudinal sliding movement with respect thereto, is a shaft E² which, at its outer end, carries a block E having a flat side and a chisel-like extremity E², and which at its inner end, carries a transverse pin I operating in a cam slot H² formed in the sleeve H.

The cam slot H² is of a shape such that it 90 cooperates with the pin I to hold the shaft 95

E³ against rotation when said shaft is in a projected position relative to the handle, in which position the flat face of the block E is disposed parallel to a plane including the 5 axes of the pin D and the shaft E³.

A coil spring G is interposed between the inner end of the handle and a shoulder or abutment F on the shaft E³ and serves to hold said shaft normally in a projected position relative to the handle. However, the shaft is adapted for depression into the handle as heretofore stated, and in this connection it will be observed by particular reference to Fig. 2, that the cam slot H² is of increasing width towards its inner end I² so that when the shaft E³ is depressed or pushed into the sleeve H, rotation of said shaft is permitted.

In view of the foregoing, the operation of 20 the device will be apparent. If the can is provided with a label, the blade C may be employed to slit said label at the inner end of the cover K. In any event, the first step in utilizing the device to effect removal of the 25 cover K from the can is to engage the chisel-like edge E² of the block between the edge of the cover flange and the annular rib of the can heretofore mentioned, with the flat side of the block disposed flat against the 30 edge of the cover flange, as shown in Fig. 4. Inward pressure then is exerted on the handle to cause the shaft E³ to be depressed into the sleeve H until the pointed end of the pivot pin D engages between the annular rib 35 on the can and the edge of the cover flange, as shown in Fig. 5. The pin I then is disposed in the wide portion of the cam slot H² and the shaft E³ is free to rotate relative to the handle. The handle then is rotated about 40 the pivot pin D in a direction to cause the flat side of the block E to exert pressure against the cover flange, so that by continued rotation of the handle the cover is forced off of the can, the shaft E³ rotating with respect to the sleeve H during this operation 45 to permit the flat side of the block E to remain in flat engagement with the edge of the cover flange whereby injury to the cover is avoided.

50 While I have illustrated and described a preferred construction for carrying my invention into effect, this is capable of variation or modification without departing from the spirit of the invention. I therefore do 55 not wish to be limited to the exact details of construction herein set forth but desire to avail myself of such variations and modifications as come within the scope of the appended claims.

59 Having thus described my invention, I claim as new and desire to secure by Letters Patent of the United States of America:

60 1. In a device of the kind described, the combination of a handle member, a pointed bar mounted thereon, and a resistance block,

70 spring mounted on said handle so as to normally extend from said handle a greater distance than said pointed bar, adaptable under pressure to recede within said handle and to turn in its mounting so that a flat side thereof of constantly bears against an object against which it is placed.

75 2. A lifter for container covers comprising a handle, a bar projecting from said handle for engagement with a covered container to form a pivot on which the handle is adapted to be turned, and a block carried by said handle and having a flat side for engagement with an edge of the cover to be lifted, said block being rotatably mounted with respect to the handle so that as the handle is turned on its pivot to pry the cover from the container continuous contact of the flat side of said block with the edge of the cover is maintained.

80 3. A lifter for container covers comprising a handle, a bar projecting from said handle for engagement with a covered container to form a pivot on which the handle is adapted to be turned, a block carried by said handle and having a flat side for engagement with an edge of the cover to be lifted, said block being rotatably mounted with respect to the handle so that as the handle is turned on its pivot to pry the cover from the container 85 said block is adapted to turn relative to the handle to maintain continuous contact of the flat side thereof with the edge of the cover, and yieldable means for holding said block normally in a predetermined position of rotation relative to the handle.

90 4. A lifter for container covers comprising a handle, a bar projecting from said handle for engagement with a covered container to form a pivot on which the handle is adapted 95 to be turned, a block mounted on said handle for rotation and depression, said block having a flat side for engagement with an edge of a cover to be lifted, and yieldable means holding said block normally in a projected 100 position relative to the handle.

105 5. A lifter for container covers comprising a handle, a bar projecting from said handle for engagement with a covered container to form a pivot on which the handle is adapted 110 to be turned, a block mounted on said handle for rotation and depression, said block having a flat side for engagement with an edge of a cover to be lifted, yieldable means holding said block normally in a projected position relative to the handle, and cam means co-operating with said yieldable means to maintain said block normally in a predetermined 115 position of rotation relative to said handle.

120 6. A lifter for container covers comprising a handle, a bar projecting from said handle for engagement with a covered container to form a pivot on which the handle is adapted 125 to be turned, a shaft mounted on said handle for rotation and longitudinal movement with

respect thereto, a block carried by said shaft, said block having a flat side for engagement with an edge of the cover to be lifted, pin and slot means limiting longitudinal movement of said shaft, and spring means constantly urging said shaft to its outermost position of longitudinal movement relative to said handle, said pin and slot means holding said shaft in a predetermined position of rotation when the shaft is in its outermost position and being formed to permit rotation of said shaft when same is moved inward from its outermost position.

In testimony whereof I affix my signature.

15 JOHN J. FLOYD.
